UNITED STATES PATENT OFFICE.

RICHARD H. ADAMS, OF TORONTO, CANADA.

MOLD FOR MOLTEN METALS AND MINERALS.

No. 830,192.

Specification of Letters Patent.

Patented Sept. 4, 1906.

Application filed September 2, 1903. Renewed January 6 1906. Serial No. 294,827.

To all whom it may concern:

Be it known that I, RICHARD H. ADAMS, of the city of Toronto, in the county of York and Province of Ontario, Canada, have invented certain new and useful Improvements 5 in Molds for Shaping Molten Metals and Minerals; and I hereby declare that the following is a full, clear, and exact description of the same.

10 This invention relates to a matrix for molding into a compact or homogeneous mass mineral and metallic matter which has been converted from a solid to a liquid state by a high degree of heat or caloric. The heat or 15 caloric employed to liquefy the material becomes latent in the liquefied mass and is partly absorbed by the mold when the molten mass has been poured therein, and causes the mold to expand and permit of the liquefied 20 mass occupying a larger bulk than the internal dimensions of the mold under normal conditions would allow of.

The expansion of the metal mold being 25 ordinarily greatly in excess of the expansion of its liquefied contents results, when the mold and its contents have cooled, in the contraction of its sides and ends against the molded mass, which renders the delivery of the molded mass exceedingly difficult. To obviate 30 this difficulty is the object of the present invention, which is accomplished by making the mold of separable sections, arranged when the mold is in its normal position to be tightly closed one against the other, and to 35 be automatically separated as the mold moves from its normal to its delivery position, this automatic action of the mold being effected by the peculiar construction and arrangement of the parts hereinafter more fully set 40 forth, and more particularly pointed out in the claims.

In the drawings, Figure 1 is a perspective view of the mold, showing the parts in their normal position. Fig. 2 is a similar view 45 showing the same parts with the mold in its overturned position. Fig. 3 is a sectional view on the lines *a a*, Fig. 1. Fig. 4 is a sectional view on the lines *b b*, Fig. 2.

Like letters of reference refer to like parts 50 throughout the specification and drawings.

The mold-section *a* consists of a side member *b* and an end member *c*, secured to or integrally formed with each other, while the

section *a'* consists of a side member *b'*, an end member *c'*, and a bottom member *d*. When the mold-sections *a* and *a'* are assembled, the side edges of the end members *c* and *c'* engage the side members *b'* and *b*, respectively, and form a practically perfect contact therewith. Along the free edges of the bottom member *d* is a groove *e* to receive the tongue *f*, forming part of the inner faces of the side member *b* and end member *c*. Extending longitudinally along the middle of the bottom member *d* is a rib *d'* to not only strengthen 65 the mold, but also to form in the molded mass a correspondingly-shaped groove. Projecting downwardly from the lower edge of the side member *b* is a flange *g*, having a slot *h* to receive a lug *i*, projecting laterally from 70 the side edge of the bottom member *d*; the dimensions of the slot *h* being slightly greater than those of the lug to admit of a limited movement of the lug therein as the sections are respectively separated and closed. Projecting outwardly from each of the side members *b* and *b'* are tapering trunnions *j*, axes of 75 which are not in the same straight line, but intersect at the middle of the mold below an imaginary line passing through the centers 80 of the inner ends of the trunnions when the mold is in its initial position, and secured to the outer face of the side members *b* and *b'*, preferably in juxtaposition to the trunnions *j*, are cams *k*, arranged to engage the bearings 85 *l*, in which the trunnions *j* are journaled.

To increase the internal dimensions of the mold for the purpose of permitting the easy delivery of its contents, the bearings *l* are made to correspond with the shape of and 90 snugly fit the tapered trunnions, so that as the geometric center of the trunnions continually change during their rotation in the bearings the variations of the inclination of the intersecting axes will cause the longitudinal 95 and lateral separation of the sections, the sections during such separation being tilted to increase the area of the mold top to greater dimensions than the bottom, the longitudinal movement of the mold-sections being limited by the limitation of the movement of the lug in the slotted flange and the lateral movement of the mold-sections being limited by the contact of the side members with the bearings, the cams being so arranged relatively to the bearings that they will permit of 100 105

the longitudinal and lateral movement of the mold-sections as the mold moves into its overturned position. As the mold rotates from its overturned to its normal position the 5 trunnions return the mold-sections to their assembled or united position, the cams *k* assisting the trunnions in the assembling of the parts and holding the parts rigidly in their assembled position by engaging the adjacent 10 faces of the bearings.

In order to provide for a perfect contact of the lid or cover with the contents of the mold, the top edge of one end member is cut away or provided with an outlet-aperture *o*, through 15 which the surplus molten material may overflow when displaced by the lid or cover *m* as it moves into position in the top of the mold, the lid or cover *m* being provided on its inner face with a rib *p* to form in the adjacent surface 20 of the contents of the mold a similar-shaped recess, the front end of the lid or cover having a weight *q* to forcibly move it into and securely hold it in contact with the mold contents.

25 When the mold is used for the purpose of shaping molten slag or stone in the production of building or paving blocks, the bearings *l* are preferably united by means of bifurcated arms *r*, forming part of the bearing-bracket *s*, which is provided with a tongue *t* to enter a corresponding socket in the carrier-frame shown and described in my concurrent application, Serial No. 171,138, filed August 28, 1903, the top of the bracket being fitted 30 with lugs *s'*, to which is hinged the rear end of the cover *m*, the arms *r* being of a sufficient length to permit of the rotation or semirotation of the mold as it moves from and returns to its normal position. The lid or cover being 35 hinged to the lugs *s'* can be moved into or out of the mold, as required, during the use of the apparatus, and by hinging the lid or cover to the bearing-bracket the mold can rotate unobstructedly from and to its normal position to respectively deliver its molded 40 contents and receive a fresh charge of molten material which is poured into the mold when in the upright position, (shown in Figs. 1 and 3,) the lid being tilted from the mold for that 45 purpose and the surplus material overflowing through the aperture *o*.

When the mold has been fully charged with its contents, the lid is lowered into the position shown in Fig. 1, engaging the top surface 55 of the contents and forming the recess therein, the contents displaced by reason of the entry of the lid into the mold and the formation of the recess overflowing through the aperture *o*. When the contents of the 60 mold have solidified, the lid or cover is raised, and the mold is turned into the overturned position shown in Figs. 2 and 4, the trunnions then separating the sections longitudinally and laterally as the mold moves into its

overturned position to relieve the molded 65 contents of the pressure of the sides and ends caused by the unequal contraction of the mold and molten mass during the cooling of the same. After the delivery of the contents the mold is returned to the position 70 shown in Figs. 1 and 3, the rotation of the trunnions during the return of the mold causing the longitudinal and lateral closing of the sections, the cams at the same time contacting the bearings and assisting the trunnions 75 to reassemble, and thereafter hold the sections securely in their reassembled condition.

Secured to the sides of the mold-sections *a* and *a'* are outwardly-projecting flanges *w* overhanging the inner faces of the bearings and the adjacent part of the trunnions to shed from the trunnions and bearings any molten material which might overflow from the top of the mold, and by doing so protect the bearings and trunnions from the injurious action of the material upon the bearing-surfacing of these parts.

Having thus fully described my invention, what I claim as new, and desire to secure by Letters Patent, is—

1. A mold consisting of two mold-sections separable longitudinally and laterally, trunnions for the mold-sections having their axes intersecting between the mold sides, bearings for the trunnions arranged to automatically cause the longitudinal and lateral separation of the mold-sections as the mold moves into position to deliver its contents and to close them together as it moves into its normal position.

2. A mold consisting of two mold-sections separable laterally and longitudinally, tapering trunnions for the mold-sections the axes of which are not in the same straight line and correspondingly-shaped bearings for the trunnions which during their rotation are arranged to cause the longitudinal and lateral separation of the mold-sections as the mold moves into position to deliver its contents and the longitudinal and lateral closing together of the same as the mold returns to its normal position.

3. A mold consisting of mold-sections, tapering trunnions for the mold-sections, correspondingly-shaped bearings for the trunnions, cams for the mold-sections adapted to engage the bearings as the mold moves into its normal position and stops to limit the longitudinal movement of the mold-sections as they separate and close, substantially as specified.

4. A mold consisting of separable mold-sections, tapering trunnions for the mold-sections, correspondingly-shaped bearings for the trunnions, said trunnions being arranged to cause the separation of the mold-sections as the mold moves into position to deliver its contents and to cause the closing

of the mold-sections as the mold returns to its normal position, cams for the mold-sections arranged to engage the bearings and assist the trunnions in the closing of the sections, a slotted guide member for one of the mold-sections and a tongue for the other mold-section of lesser dimensions than and contained in the guide member to limit the longitudinal movement of the sections, substantially as specified.

5 5. A mold consisting of separable mold-sections, tapering trunnions for the mold-sections, correspondingly-shaped bearings for the trunnions, said trunnions being arranged to cause the separation of the mold-sections as the mold moves into position to deliver its contents and to cause the closing of the mold-sections as the mold returns to its normal position, cams for the mold-sections arranged to engage the bearings and assist the trunnions in the closing of the sections, a slotted guide member for one of the mold-sections and a tongue for the other mold-section of lesser dimensions than and contained in the guide member to limit the longitudinal movement of the sections, arms to which the bearings are connected and a yoke uniting the arms, substantially as specified.

10 6. A mold consisting of separable mold-sections, tapering trunnions for the mold-sections, correspondingly-shaped bearings for the trunnions, said trunnions being arranged to cause the separation of the mold-sections as the mold moves into position to deliver its contents and to cause the closing of the mold-sections as the mold returns to its normal position, cams for the mold-sections arranged to engage the bearings and assist the trunnions in the closing of the sections a slotted guide member for one of the mold-sections and a tongue for the other mold-section of lesser dimensions than and contained in the guide member to limit the longitudinal movement of the sections, and a lid for the mold hinged to the bearings, substantially as specified.

15 7. A mold consisting of separable mold-sections, tapering trunnions for the mold-sections, correspondingly-shaped bearings for the trunnions, said trunnions being arranged to cause the separation of the mold-sections as the mold moves into position to deliver its contents and to cause the closing of the mold-sections as the mold returns to its normal position, cams for the mold-sections arranged to engage the bearings and assist the trunnions in the closing of the sections, a slotted guide member for one of the mold-sections and a tongue for the other mold-section of lesser dimensions than and contained in the guide member to limit the longitudinal movement of the sections, arms to which the bearings are connected, a yoke uniting the arms, and a lid hinged to the

bearing-arms and adapted to enter the mold, substantially as specified.

20 8. A mold consisting of separable mold-sections, tapering trunnions for the mold-sections, correspondingly-shaped bearings for the trunnions, said trunnions being arranged to cause the separation of the mold-sections as the mold moves into position to deliver its contents and to cause the closing of the mold-sections as the mold returns to its normal position, cams for the mold-sections arranged to engage the bearings and assist the trunnions in the closing of the sections, a slotted guide member for one of the mold-sections and a tongue for the other mold-section of lesser dimensions than and contained in the guide member to limit the longitudinal movement of the sections and a lid for the mold hinged to the bearings, and an overflow-aperture for the mold, substantially as specified.

25 9. A mold consisting of separable mold-sections, tapering trunnions for the mold-sections, correspondingly-shaped bearings for the trunnions, said trunnions being arranged to cause the separation of the mold-sections as the mold moves into position to deliver its contents and to cause the closing of the mold-sections as the mold returns to its normal position, cams for the mold-sections arranged to engage the bearings and assist the trunnions in the closing of the sections, a slotted guide member for one of the mold-sections and a tongue for the other mold-section of lesser dimensions than and contained in the guide member to limit the longitudinal movement of the sections, arms to which the bearings are connected, a yoke uniting the arms, a lid hinged to the bearing-arms and adapted to enter the mold, and an overflow-aperture for the mold, substantially as specified.

30 10. A mold consisting of separable mold-sections, tapering trunnions for the mold-sections, correspondingly-shaped bearings for the trunnions, said trunnions being arranged to cause the separation of the mold-sections as the mold moves into position to deliver its contents and to cause the closing of the mold-sections as the mold returns to its normal position, cams for the mold-sections arranged to engage the bearings and assist the trunnions in the closing of the sections, a slotted guide member for one of the mold-sections and a tongue for the other mold-section of lesser dimensions than and contained in the guide member to limit the longitudinal movement of the sections, a lid for the mold hinged to the bearings, projecting flanges for the trunnions and bearings connected to the sides of the mold-sections, substantially as specified.

35 11. A rotatable mold consisting of two mold-sections separable longitudinally and

laterally, oppositely-disposed trunnions for the mold-sections the axes of which are not in the same straight line but intersect between the opposite sides of the mold, stationary bearings for the trunnions to effect the longitudinal and lateral separation and the corresponding closing together of the mold-sections as the geometric centers of the

trunnions change during their revolution therein.

Toronto, July 23, A. D. 1903.

R. H. ADAMS.
